JAMES V. THOMPSON AND HOWARD C. DEITZ, OF SPENCER, WEST VIRGINIA.

CLOTHES WASHER.

Application filed March 25, 1927. Serial No. 178,353.

Our present invention has reference to a clothes washing machine.

The primary object of our invention is to dispose with the ordinary clothes cylinder in a rotary or oscillatory type of clothes washing machines and to substitute in lieu thereof clothes receptacles in the nature of angularly disposed reticulated baskets whereby each basket not only serves as a clothes retainer but as an agitator for thoroughly stirring up the saponaceous fluid in the tub as the baskets are revolved or oscillated so that the said fluid will not only pass through and act upon the clothes in each basket but will be separately disturbed and agitated by each basket and forcibly directed from one onto and through the adjacent baskets and whereby the clothes will be cleaned in an easy and expeditious manner.

A still further object is the provision of a washing machine that includes a horizontally supported tub having a shaft extending centrally therethrough, and means for imparting motion to the shaft, said shaft having fixed thereon at spaced intervals spiders, the angle arms of which being notched for the reception of a reticulated clothes containing basket therein, each of said baskets being normally closed by a reticulated cover, each of said baskets not only serving as a clothes receptacle but as a paddle or agitator for thoroughly mixing and stirring the saponaceous fluid in the tub to cause the latter to be forced through the several baskets and to act on the clothes therein to thoroughly clean such clothes in an expeditious manner and with only a small requirement of power.

To the attainment of the above broadly stated objects and many others which will present themselves as the nature of the invention is better understood, the improvement further resides in certain other novel features of construction, combination and operative association of parts, one satisfactory embodiment of which is disclosed by the accompanying drawings.

In the drawings:

Figure 1 is a perspective view of a clothes washing machine in accordance with this invention.

Figure 2 is an end view thereof with the tub in section.

Figure 3 is an elevation of our improvement per se.

Figure 4 is a side elevation of one of the

arms of the spider showing one of the baskets and frame in section.

As disclosed by the drawings, we preferably make use of a cylindrical tub 1 supported horizontally by feet 2. The tub, of course, is provided with a normally closed door 3 whereby access may be had to the interior thereof.

Journalized centrally and longitudinally through the tub there is a shaft 4. This shaft may have on one of its ends a wheel 5 that may be directly connected to either friction or pulley wheels mounted on a shaft 7 and revolved by any suitable source of power (not shown). The pulley wheels have associated therewith shift mechanism 8, whereby the several wheels 9 may be actuated to turn the wheel 5, and consequently the shaft 4 in opposite directions.

Keyed on the shaft 4, preferably at equidistantly spaced intervals there are plates or castings that provide spiders 10. The arms 11 which radiate from the hub of each spider 10 are preferably arranged right angularly with respect to each other and the said arms having their outer portions widened, as at 12, and notched, as at 13, from one of their edges. These notches provide substantially rectangular pockets and seated in the notches or pockets in the aligning arms of the several spiders there are the reticulated portions 14 of clothes receiving baskets. Each arm 11, on the inner wall provided by the notches 13, is preferably formed with an outstanding ear 15 and through these aligning ears a pivot 16 passes. To the pivots there are secured the frame portions 17 of the reticulated covers 18 for the several baskets. The outer elements of each frame 17, in a line with the arms 19 provided by the outer notched portions of the arms 12, have openings therethrough, as at 20. The arms 19 preferably have their outer corners notched or otherwise reduced forming the same with what may be termed fingers 21 that are received through the openings 20. Fixed on the outer edge of each arm 19 there is a spring catch member 22, the said members passing through the openings 20 and overlying and contacting the portions of the frame outward of the said openings and whereby the covers are effectively latched in closed position.

By providing baskets on the arms of the spiders in a washing machine, and mount-

ing the spiders for either rotary or oscillatory movement, each basket serves as an agitator for the saponaceous fluid in the tub 1, so that this fluid will be forced through the clothes in each basket and will also be directed from one basket forcibly through the adjacent baskets so that the clothes will be cleaned in an easy and expeditious manner and with the employment of only a comparatively small amount of power.

The simplicity and advantages of the invention will be understood and appreciated by those skilled in the art to which such invention relates and a further detailed description will not be required.

Having described the invention, we claim:—

1. A washing machine including a cylindrical tub having legs supporting the same horizontally, a shaft journaled centrally through the tub, spiders on the shaft, each of said spiders having a plurality of radially disposed arms each having a notch therein, reticulated clothes receiving baskets seated in the notches, a reticulated closure for each basket hingedly secured to the arms

of the spiders and latching means carried by the arms of the spiders for engaging with the closures.

2. A washing machine including a horizontally arranged cylindrical tub, a shaft journaled centrally through the closed ends of the tub, equidistantly spaced spiders keyed on the shaft, and each having a plurality of radially disposed arms and each of said arms having a notch therein, rectangular clothes receiving baskets seated in the notches, a reticulated closure for each basket, each of said closures including a frame whose inner edge is hingedly connected with the respective spiders, and whose outer end is formed with openings to receive the outer portions of the notched spiders therein, and spring catch members on the outer edges of the spiders to be received through said openings in the frames of the closures for latching the closures over the baskets.

In testimony whereof we affix our signatures.

JAMES V. THOMPSON.
HOWARD C. DEITZ.
